UNITED STATES PATENT OFFICE

102,696

DESIGN FOR A SOAP CHIP DISPENSER OR SIMILAR ARTICLE

Charles Miller, Madison, Wis.

Application April 15, 1936, Serial No. 62,142

Term of patent 3½ years

To all whom it may concern:

Be it known that I, Charles Miller, a citizen of the United States, residing at Madison, in the county of Dane and State of Wisconsin, have invented a new, original, and ornamental Design for a Soap Chip Dispenser or Similar Article, of which the following is a specification, reference being had to the accompanying drawing, forming part thereof.

chip dispenser or similar article showing my new design.

I claim:—

The ornamental design for a soap chip dispenser or similar article, as shown.

CHARLES MILLER.
